UNITED STATES PATENT OFFICE.

ROLAND CHILTON, OF KEYPORT, NEW JERSEY, ASSIGNEE TO AEROMARINE PLANE & MOTOR COMPANY, A CORPORATION OF NEW YORK.

COMBINED MAGNETO AND STARTER UNIT.

Application filed September 15, 1921. Serial No. 500,807.

To all whom it may concern:

Be it known that I, ROLAND CHILTON, a subject of the King of England, and resident of Keyport, in the county of Monmouth and

5 State of New Jersey, have invented certain new and useful Improvements in Combined Magneto and Starter Units, of which the following is a specification.

The invention relates in general to a combined magneto and starter unit for attachment to an internal combustion engine, and the invention specifically relates to such an attachment for use in connection with an engine of the type used in aeroplane power 10 constructions for taking power off of the engine shaft, for actuating magnetos and the like, and for conveying rotary power to the shaft for the purpose of starting the engine.

20 In engines of the aeroplane type it is usual to mount the propeller at one end of the main drive shaft of the engine which leaves the opposite end as an available place to mount an apparatus of the class herein described. The invention therefore pertains to an attachment for engaging an aeroplane engine at the free end of its main shaft and in position so as to make convenient engagement with the exposed free end of 25 the engine shaft.

It is understood that in aeroplane constructions lightness of weight, and accordingly compactness of construction and the elimination of waste material, is vitally 30 necessary. At the same time it is required that structures of the class outlined must be made sufficiently rugged to withstand severe strains to which devices of this character are subjected.

40 Accordingly, one of the objects of the invention is to provide a simple, compact, rugged construction which at the same time will be light in weight and which will function largely through the same mechanism both to start the engine and to receive power 45 from the active engine for the purpose of actuating magnetos and the like, usually driven from the engine shaft.

As the magneto is one such instrument 50 taking power from the engine shaft and which requires ready accessibility, the present disclosure features the compact mount-

ing of a magneto or a plurality of magnetos on a frame structure which is designed primarily to accommodate a starter for the engine. 55

Accordingly, another object of the invention is to provide a simple form of combined starter and magneto construction which can be formed compactly to economize in space 60 disposition and thus feature lightness in construction with efficiency in operativeness.

Still another object of the invention and incidental to the last recited object is to provide a structure in which the several 65 movable parts are held in a preset desired relation and in such manner as will minimize if not eliminate rattling or other evidence of looseness of fit between the parts.

Various other objects and advantages of 70 the invention will be in part obvious from an inspection of the accompanying drawings and in part will be more fully set forth in the following particular description of one form of mechanism embodying my invention, and the invention also consists in certain new and novel features of construction 75 and combination of parts hereinafter set forth and claimed.

In the accompanying drawings:—

Figure 1 is a vertical sectional view through an attachment illustrating a preferred embodiment of the invention and shown mounted in position on an aeroplane engine; and

Figure 2 is a view partly in front elevation and partly in vertical section on the line 2—2 of Figure 1.

In the following description and in the claims, parts will be identified by specific 90 names for convenience of expression but they are intended to be as generic in their application to similar parts as the art will permit.

In the drawings there is disclosed part of 95 a conventional form of internal combustion engine 10 shown adjacent its main crank shaft 11, which shaft is mounted in bearings 12 with an end of the shaft disposed adjacent to an opening 13 formed in the engine casing, as is usual in a well known engine construction.

100 The device featured in this disclosure is in the form of an attachment and includes

a mechanism containing hollow casing 14 having an exposed end 15 outlined by flange 16 which is demountably secured to the open end 13 of the engine casing by means of bolts 17. It is understood that the bottom of the engine casing 18 constitutes an oil pan and that lubricant in the casing is splashed through the opening 13 and into the hollow casing 14 by the rotation of the piston 10 cranks 19.

The casing includes an upstanding front wall 20 which constitutes the main structural part of the frame or casing 14. A power transmission shaft 21 is journalled adjacent its forward end in anti-friction bearings 22 formed in the wall 20, extends through the hollow casing and projects from the open end 15 so as to extend into the engine casing. The exposed end of the main drive shaft is secured to the crank shaft and constitutes, in effect, an extension of the shaft.

The casing 14 is designed to provide a support for an electric starter motor 23 and is flanged to provide a support for a front cover plate 24. The motor 23 is provided with a pinion 25, which drives a gear 26 at the forward end of the power transmission shaft 21 through starter mechanism indicated generally by the reference character 27 and which includes a shiftable pinion 28, all of which is more fully described in my copending application for internal combustion engine starter, Serial No. 471,002, filed May 19th, 1921. The starter mechanism is designed to be operated manually by means of a hand crank 29 engaging the shiftable pinion 28.

Referring to the disclosure in Figure 2, it is noted that the attachment which constitutes the casing for supporting the starter mechanism is provided on opposite sides of the starter mechanism with integrally formed and outwardly extending brackets 30 and 31. These brackets constitute respectively a support for a pair of magnetos 32 and 33 of conventional construction and which are thus balanced on opposite sides of the starter construction. The magnetos are demountably held in place by means of straps 34. A magneto cross shaft 35 is journaled adjacent opposite ends in bearings 36 formed in the casing 14 and is connected to the power transmission shaft 21 through a worm gear drive 37. The driving element or shaft 38 of each magneto is coupled to the adjacent end of the magneto cross shaft by means of a coupling 39, preferably of the flexible type to compensate for any possible disalignment between the magneto shafts 38 and the magneto cross-shaft 35.

In the illustrated showing in Figure 2, the flanges 30 and 31 supporting the magnetos are shown to be horizontally disposed, but it is within the scope of the present dis-

closure to extend these flanges at an angle to the horizontal. This will obviously necessitate a small change in the manner of gearing the magneto shaft to the power transmission shaft.

By means of a device of this character it is possible to attach either or both the starter and magneto shaft or shafts to the main drive shaft of the engine and to make the coupling therewith conveniently to the free end of the shaft opposite the end carrying the propeller. The attachment is designed to fit the usual opening found in engines of the type discussed and by the obvious use of a suitable adopter plate the attachment can be readily mounted on a form of opening differing from the form for which the attachment is designed. Ready access is provided to the different parts, for instance, the hand crank can be inserted to operate the mechanism manually and the magneto can be readily demounted due to the character of coupling utilized. However, the driving shaft and gearing contained within the casing and driven from the magnetos are fixedly mounted in position thus permitting the use of bearings and other anti-friction devices. At the same time the starter mechanism is maintained in preset position thus minimizing any tendency of these parts to become disarranged.

The present invention particularly features compactness of parts with the magnetos positioned close to the starter mechanism and positioned in the available space in advance of the engine and in rear of the space necessarily occupied by the starter mechanism. The starter mechanism overlaps the power transmission shaft, which is, in effect, a continuation of the engine shaft, and thus the starter motor is conveniently disposed between the gear train forming part of the starter mechanism and the engine thus utilizing space which would be otherwise lost. Considered in another way it is noted that the starter mechanism occupies and thus utilizes the space between the magnetos which would be otherwise lost due to the necessity of providing a driving connection with the main shaft from the space between the magnetos. 100 105 110 115

As the mechanism carried by the attachment is opened to the lubricant splash chamber of the engine the movable parts are lubricated by the splash within the engine and it is therefore to be considered that both the magneto actuated mechanism and the starter actuated mechanism are enclosed in a lubricated space. 120

While I have shown and described, and have pointed out in the annexed claims, certain novel features of my invention, it will be understood that various omissions, substitutions and changes in the form and details of the device illustrated and in its oper- 190

ation may be made by those skilled in the art without departing from the spirit of the invention.

Having thus described my invention, I claim:

1. In a device of the class described, the combination with an internal combustion engine including a casing having an opening in one side thereof and a main drive shaft accessible from the outside of the casing through said opening, of a combined magneto and starter unit provided with means for mounting the same on the engine casing adjacent the accessible part of the main shaft and constituting a closure for said opening, said unit including a power transmitting shaft constituting an axial extension of the main drive shaft and provided with means at one end for coupling the same with said main drive shaft, a magneto operatively connected to the power transmitting shaft intermediate its ends to be driven thereby, a starter mechanism adapted to be operatively connected to the power transmitting shaft to start the main drive shaft adjacent its outer end.
2. In a device of the class described, the combination of an engine attachment comprising a mechanism supporting frame provided with means for securing the same to an engine, a power transmitting shaft journaled therein and provided with coupling means for connecting the same to the shaft of the engine and in alignment therewith, means for mounting a magneto in the frame in position to be driven by said power transmitting shaft, a gear carried by said shaft for driving the magneto, means for mounting a starter mechanism in said frame in position to be operatively connected to the power transmitting shaft thereby to start the engine and a second gear carried by said shaft and adapted to be rotated by the starter mechanism.
3. In an aeroplane, the combination with an engine having a main drive shaft with a propeller carrying end and a normally free end, of a unit adapted to be mounted in position at the free end of said shaft, a power transmission shaft carried by the unit in driven and driving engagement with said free end, a magneto and a starter mechanism carried by the unit and both in operative engagement with the power transmitting shaft whereby power may be taken off or conveyed to the engine shaft at the end opposite to the propeller and a hand crank operatively connected to the power transmission shaft to rotate the same manually.
4. In a device of the class described, the combination of an engine having a main drive shaft, a replaceable unit provided with means for securing the same to the engine, mechanism in said unit including a magneto, a starter and a single coupling device for

connecting both the magneto and starter to the engine shaft and means carried by the unit and operatively disposed to engage said coupling device for driving said main shaft manually.

5. In a device of the class described, the combination of an attachment for an internal combustion engine comprising a frame provided with a centrally positioned starter mechanism and means constituting a part of the frame for accommodating a pair of magnetos balanced on opposite sides of the starter mechanism.

6. In a device of the class described, the combination of a frame provided with a centrally positioned starter mechanism and power transmission shaft adapted to be connected to the drive shaft of an engine, means for accommodating a pair of magnetos balanced on opposite sides of the starter mechanism, and coupling means carried by the frame for connecting the magnetos to said power transmitting shaft.

7. In a device of the class described, the combination of a mechanism supporting frame, a magneto cross shaft journaled in said frame, magnetos in driving engagement therewith at opposite ends thereof, a starter mechanism including a part thereof overlapping said cross shaft and disposed between the magnetos thereby to economize in space and incidentally provide a light structure.

8. In a device of the class described, the combination of a frame having one side adapted to contact with an engine, and the opposite side exposed, a power transmitting shaft extending from the exposed side to the side that contacts with the engine, a magneto cross shaft lapping the power transmitting shaft and geared thereto, starter mechanism overlapping the cross shaft and including means for engaging the power shaft at the end adjacent the exposed side of the frame.

9. In a device of the class described, the combination of an engine casing having an opening in the side thereof, an attachment casing having an opening constituting a horizontal continuation of the opening in the engine casing, starter and magneto driving mechanism housed in said attachment casing and including a power transmission shaft extending through the openings of the casings and constituting the sole element in said opening.

10. In a device of the class described, the combination of a unit adapted to be attached to an internal combustion engine and including a frame provided with means for attaching the same to the internal combustion engine, said frame having means for mounting a separable magneto and for mounting a separable starter motor and provided with mechanism constituting a part of the unit

- and including two sets of gear drives, one for operatively connecting the magneto and the other for operatively connecting the starter with an active element of the engine 5 to which the frame is attached.
11. An attachment for an internal combustion engine including a mechanism containing housing, means for demountably securing the attachment to the engine, starter 10 mechanism including a gear train contained in said housing constituting a permanent part of the unit and adapted to be connected to an active element of the engine, a readily separable magneto carried by said attachment 15 and exposed exteriorly of the housing and a driven shaft and a second gear train constituting a driving connection between an element of the housed starter and the external magneto.
12. In an internal combustion engine, the combination of two magnetos arranged in spaced apart relation across one end thereof, a starter disposed in the space between the magnetos and means including a common 20 shaft having a coupling means at one end for operatively connecting the starter and magnetos with the engine.
13. In a device of the class described, the combination with an internal combustion engine having an extension at one end, a pair 25 of magnetos spaced apart transversely on said extension, a driving connection between the magnetos and a starter disposed between the magnetos and including a gear drive 30 operatively connected to said driving connection.
14. In a device of the class described, the combination with an internal combustion engine having an extension at one end and opened thereto, a pair of magnetos spaced apart transversely on said extension, a driving connection including a common shaft between the magnetos and housed within the extension and a starter disposed between the magnetos and including a drive shaft geared 35 to said common magneto shaft.
15. A demountable unit including a casing provided with an opening outlined by a securing flange for mounting the unit on an internal combustion engine, said unit provided with means for demountably positioning a magneto thereon, a shaft carried by the casing for connection with such magneto, a starter carried by the casing and a single power transmission shaft with an end 40 projecting beyond the casing and adapted to be connected to an engine shaft and said transmission shaft within the casing providing a common driving connection with both the starter and the magneto shafts.
